DESIGN FOR AN ELECTRICAL PLUG HOUSING

Jerome Neustadt, New York, N. Y.

Application March 2, 1948, Serial No. 144,865

Term of patent 14 years
(Cl. D26—1)

To all whom it may concern:

Be it known that I, Jerome Neustadt, a citizen of the United States of America, residing at New York, in the county of New York and State of New York, have invented a new, original, and ornamental Design for an Electrical Plug Housing, of which the following is a specification, reference being had to the accompanying drawing, forming part thereof.

In the drawing,

Fig. 1 is a perspective view of the electrical plug housing, showing my new design;

Fig. 2 is a side elevation of Fig. 1, showing my new design; and

Fig. 3 is an end elevational view of the electrical plug housing, showing my new design.

I claim:

The ornamental design for an electrical plug housing, as shown.

JEROME NEUSTADT.
